(57) **CLAIM**

The ornamental design for a floor mat for an automobile, as shown and described.

DESCRIPTION

FIG. 1 is a slight perspective top view of a floor mat, according to a first exemplary embodiment of the invention; and, FIG. 2 is a slight perspective top view of another floor mat, according to a second exemplary embodiment of the invention.

The lines on the top side of the floor mats are grooves. The bottom of the floor mats are flat and devoid of surface ornamentation.
